UNITED STATES PATENT OFFICE.

JOHN WICKS, OF OAK PARK, ILLINOIS, ASSIGNEE, BY MESNE ASSIGNMENTS, TO AUTOMATIC ELECTRIC INC., OF CHICAGO, ILLINOIS, A CORPORATION OF DELAWARE.

MEASURED-SERVICE TELEPHONE SYSTEM.

Application filed October 30, 1920. Serial No. 420,715. Renewed May 28, 1925.

The present invention relates in general to measured service telephone systems, but more particularly to automatic party line measured service systems, and the principal object of the invention is the provision of a system of this kind wherein each station on a party line is provided with a meter at the exchange, and wherein each meter is adapted to be separately connected for registering calls whenever its associated station is calling. Incidental objects consist in the provision of improved circuit arrangements whereby the foregoing is accomplished as efficiently as possible and without complicated mechanism at the subscriber's station, all of which will be described fully hereinafter with reference to the accompanying drawings, in which Figs. 1 and 2 show by means of the usual circuit diagrams the essentials of a telephone system embodying the principles of the invention.

Referring to Fig. 1, the substations A and A' are ordinary automatic substations such for example as is shown in the U. S. patent 25 to Smith, No. 1,221,235, granted April 3, 1917. The two telephones are connected in bridge of the line conductors 11 and 12 in the usual manner, the line being what is commonly known as a two party line. At 30 the exchange the line conductors terminate in the individual line or trunk selecting switch C. The line switch C is of the well known rotary type, in which the wipers have no normal position and move in a forward direction only. The function of a switch of this kind is to extend its associated line, when calling, to an idle trunk line extending to a first selector switch, and to this end the line switch C, in common with a plurality of similar line switches, is given access to a group of such trunk lines. One of the trunk lines to which the line switch C has access is shown in the drawing and extends by way of the repeater D to the first selector E, Fig. 2. The repeater D comprises a group of relays as shown and is provided for the purpose of controlling the meters associated with any calling line which happens to be using this particular trunk line, as will be explained fully later on.

The selector E is one of a plurality of similar selectors whose function it is to extend the calling lines to desired main groups of called lines, and there may be only one selector switch, or a plurality in any given

connection depending on the size of the system. As shown herein it is assumed that both first and second selectors are used, and one of the latter type of switches is shown and is indicated by the reference character F. 60 The second selectors have access to trunk lines extending to connector switches which in turn have access to the subscribers' lines. Inasmuch as selector switches of the type mentioned are well known, only the wipers of selectors E and F are shown in the drawing and the circuits are omitted. For a complete disclosure reference is made to the book entitled Automatic Telephony, by Smith and Campbell, published by the McGraw-Hill Book Company in 1914. 65

One of the trunk lines accessible to the second selector F is shown in the drawing and extends to the connector H. This switch, as well as the selector switches, is of the well known Strowger vertical and rotary type and has access to 100 subscribers' lines, one of which is the line extending to substation A'. Although the circuits of the connector are well known they are shown in full, 80 largely because of the fact that the connector circuits enter into control of the substation meters, and it would be inconvenient to explain the operation of the meters without including the complete connector circuit. 85

The meters, or call registers M and M', are associated, respectively, with substations A and A' and may be located at any preferred point in the exchange, as for example in a cabinet, or they may be mounted on the switchboard with the line switches. The meters are directly controlled by relays 24 and 25 which in turn are controlled from the repeater D in the trunk circuit. This repeater contains means which is selectively operated in accordance with a particular calling station on a party line in order to determine which of the meters associated with said line should be operated. The manner in which the meters are thus selectively controlled is the principal feature of the invention and the explanation thereof will now be proceeded with.

For this purpose it will be assumed that the subscriber at substation A, Fig. 1, desires to call a subscriber at substation A', Fig. 2. When the receiver is removed a circuit is completed over the line conductors 11 and 12 for the line relay 15 of the line switch C. Upon energizing, the line relay closes a 105

circuit for the switching relay 14 in series with the stepping magnet 16 at its armature 21, and at its armature 22 connects test wiper 32 to the above circuit at a point midway between the said relay and magnet. The operation now depends upon whether the trunk line with which the switch wipers are associated is busy or idle. If this trunk line is busy the test contact engaged by the test wiper 32 will have a ground potential upon it, the switching relay 14 will be short circuited, and the stepping magnet 16, being supplied with direct ground via the test wiper, will operate as a buzzer to advance the switch wipers step by step in search of an idle trunk line. We may assume, however, in the present case that when the call is initiated the wipers of the line switch C are standing upon the set of bank contacts shown in the drawing, and it may be assumed furthermore that the trunk line terminating in these bank contacts is idle. Under these circumstances when the line relay 15 is energized no rotary movement of the switch will take place, and the switching relay 14 will energize at once. Upon attracting its armature 19 relay 14 connects ground to the test wiper 32 in order to make the selected trunk line busy, closes a contact in the meter control circuit at its armature 18 and at its armatures 17 and 20 extends the line conductors 11 and 12 by way of the working contacts of the said armatures, wipers 30 and 32, bank contacts 34 and 37, conductors 38 and 41, armatures 59 and 62 and their resting contacts, windings of the differential relay 52, and the windings of the line relay 53 and the retard coil 75 to battery and ground, respectively.

When the calling line is extended to the repeater D as above explained the line relay 53 is energized over the line circuit and at its armature 64 closes a circuit for the slow acting release relay 54. Upon energizing, relay 54 prepares a circuit for the slow acting relay 56 at armature 66, and at armature 67 connects ground to the release trunk conductor 86, thereby completing a holding circuit which extends back to the line switch C by way of the said conductor 86, conductor 40, test contact 36, test wiper 32, armature 19 and its working contact, winding of the switching relay 14, and the winding of the stepping magnet 16 to battery. This circuit is established before the line relay 15 has had time to deenergize and serves to maintain the switching relay 14 energized throughout the duration of the connection. Ground is also placed on the private normal conductor 13 which extends to multiply connected test contacts in the banks of the connector switches which have access to the party line shown, whereby the said line is made busy in the usual manner.

When the line relay 53 energizes it also

closes a bridge across the trunk conductors 85 and 87, which may be traced from the conductor 85 by way of armature 71 and its resting contact, normally closed contact springs controlled by armature 59, upper winding of the electropolarized relay 51, winding of the retard coil 74, working contact of armature 65 and the said armature, and the normally closed contact springs controlled by armature 62 to conductor 87. When this bridge is closed a circuit is completed in the usual manner for the line relay (not shown) of the first selector E, and the line and release relays of this selector switch are accordingly energized to prepare the selector for operation in the usual manner. It should be stated at this point that although the upper winding of the electropolarized relay 51 at the repeater D is in series with the line relay of the first selector, relay 51 is not operated at this time because of the opposing effect of its polarizing winding, the latter winding being now supplied with current from the grounded release trunk conductor 40. Relay 51 is so adjusted that it requires the combined effect of its two windings to operate it, and it will not operate from either winding alone, or when the two windings are in opposition to each other.

The calling subscriber may now operate his calling device S in accordance with the first digit in the desired number. As a result a series of interruptions is produced in the line circuit and the line relay 53 at the repeater D is caused to deenergize momentarily a plurality of times. At each deenergization relay 53 sends an impulse of current to relay 56 and since this relay is slow acting it remains in operated position until the impulses cease. In its energized position relay 56 closes the bridge across the trunk conductors 85 and 87 over a direct path which includes only the armature 71 and its working contact, the impulsing contact at armature 65 of the line relay 53, and the normally closed contact springs controlled by armature 62. This direct bridge is opened by the line relay 53 each time it deenergizes. In addition to the operations already described relay 56 short circuits the retard coil 75 at its armature 73 and at its armature 72 closes a circuit for relay 55. The latter relay upon energizing locks itself to the release trunk conductor by means of its armature 69, and short circuits the upper and lower windings of the differential relay 52 by means of its armatures 68 and 70. Relay 52 is thus permanently disconnected from the circuit. The short circuiting of retard coil 75 and the closure of the direct bridge across the trunk are the usual operations which are provided for in order to improve the line and trunk circuits for the transmission of impulses.

In response to the interruptions in the

bridge produced at armature 65 of the line relay 53, the selector E is operated in the usual manner to select a group of trunk lines extending to second selector switches, after which the switch operates automatically to select and connect with an idle one of these trunk lines. The connection is thus extended to some second selector and we will assume that the second selector F is the one taken for use. 10

The calling subscriber may now operate his calling device in accordance with the second digit in the desired number. As before, a series of interruptions is produced in the line circuit, and these interruptions are repeated by the line relay 53 of the repeater D into the trunk circuit which now extends through to the second selector F. This second selector is accordingly operated to select a group of connector switches, after which its wipers are automatically rotated to select and connect with a trunk line leading to an idle connector switch in the selected group. It will be assumed that the connector taken for use is the connector H, and when the trunk line conductors are extended through to the line relay 101 of this connector said line relay will be energized. Upon attracting its armature 114, relay 101 closes a circuit for the slow acting release relay 102 which, upon energizing, prepares the vertical magnet circuit at its armature 115, and at its armature 116 connects ground to the release trunk conductor 92, thereby establishing a holding circuit for the preceding switches in the usual and well known manner. This holding circuit extends back to both selector switches and is established and extended by each of said switches in turn, being always grounded at the last switch in any series of switches, which has been operated. Although not shown in full here, holding circuits of this kind are well known and are shown in the publication Automatic Telephony, previously referred to. 30

The calling subscriber may now operate his calling device in accordance with the next digit in the number. The resulting interruptions in the line circuit are repeated as before by the line relay 53 of the repeater, and in consequence the line relay 101 of the connector H is caused to deenergize a plurality of times, a circuit being closed for the vertical magnet 108 at each deenergization as follows: ground at G⁴, armature 114 and its resting contact, armature 115 and its working contact, off normal springs 111 and 113, winding of the slow acting relay 103, and the winding of the vertical magnet 108 to battery. By the operation of the vertical magnet the connector shaft is raised step by step and the wipers 140-143, inclusive, are brought to rest opposite the level of bank contacts in which the line of substation A² is located. The slow acting relay 103 is energized in series with the vertical magnet and retains its armature 117 attracted throughout the vertical movement of the switch, thus maintaining the vertical magnet circuit intact after the off normal springs have been shifted, which occurs on the first vertical step. At the end of the vertical movement, relay 103 is deenergized and transfers the operating circuit to the rotary magnet 109. 75

The calling subscriber may now call the next and final digit in the number. The resulting interruptions in the line circuit are repeated as before and the line relay 101 is again deenergized a plurality of times, this time, however, sending impulses to the rotary magnet over the following path: ground at G⁴, armature 114 and its resting contact, armature 115 and its working contact, off normal springs 111 and 112, armature 117 and its resting contact, resting contact of armature 122 and the said armature, armature 129 and its resting contact, and the winding of the rotary magnet 109 to battery. In response to these impulses the rotary magnet 109 is operated to rotate the switch wipers into engagement with the particular set of bank contacts in which the line of substation A² is terminated, these bank contacts being indicated in the drawing by reference characters 144, 145, and 146. Relay 106 is energized in parallel with the rotary magnet and being slow acting holds its armatures attracted throughout the rotary movement. At its armature 124, relay 106 connects the test wiper 142 to the winding of the test relay 105 and at its armature 125 a shunt is connected around the break contact at the armature 122 of the test relay. This latter operation is to guard against the possibility of the rotary magnet circuit being opened by the operation of the test relay in case the test wiper should engage grounded test contacts while the switch is rotated. 90

Assuming now that the called line is busy when connection therewith is established, as described in the foregoing, when the test wiper 142 comes to rest in engagement with test contact 145 it will encounter a ground potential and test relay 105 will be energized. The test relay locks itself at its armature 121 (when relay 106 falls back an instant later), breaks the rotary magnet circuit at armature 122, and at armature 123 connects a lead from the busy signalling machine to the lower side of the line. An audible busy signal is thus transmitted to the calling subscriber, and being advised thereby that the called line is for the time being inaccessible he will replace his receiver. 115

If the called line is idle when connected with, as described in the foregoing, the test wiper 142 will find no ground potential on test contact 145 and the test relay 105 will 130

not be energized. Then when the slow acting relay 106 falls back a circuit is completed for the switching relay 107 as follows: from the grounded release trunk conductor 92 by way of armature 121 and its resting contact, upper winding of relay 107, resting contact of armature 124 and the said armature, test wiper 142, test contact 145, winding of the switching relay 14', and the winding of the stepping magnet 16' to battery. Relays 107 and 14' are energized in series over the above circuit and the latter relay clears the called line conductors of their normal battery and ground connections in the line switch C'. It is noted that due to a mechanical interlocking device controlled by the line relay 15', which has not been energized, relay 14' is operated only about half way, and the line switch wipers are not connected up.

In the connector H when the switching relay 107 is energized it establishes a locking circuit for itself at its armature 128, grounds the test wiper 142 at armature 127, 25 opens the rotary magnet circuit at armature 129, and at armatures 126 and 130 connects up the upper and lower line wipers 140 and 143. Ringing current from the generator GEN is now projected out over the called line in 30 the usual manner to operate the bridged ringer at substation A², thereby notifying the subscriber that he is being called. It will be noticed that the return path for the ringing current includes the upper winding 35 of the ring cut off relay 104, and when the called subscriber answers by removing his receiver the said ring cut off relay is energized, establishing a locking circuit for itself at its armature 119. Relay 104 also opens 40 the ringing circuit at its armatures 118 and 120, and at the working contacts of these same armatures finally completes the talking circuit. The transmitter at substation A² is now supplied with talking battery through 45 the windings of the double wound back bridge relay 100, which is immediately energized over the called line. Upon operating, relay 100 reverses the incoming trunk conductors 91 and 93 as regards their connection to the windings of the line relay 101 and therefore reverses the direction of current flow in the trunk conductors 85 and 87, and in the upper winding of the electro-polarized relay 51 which is included in the 50 bridge across these conductors at the repeater D. The two windings of relay 51 now assist each other and the relay is operated. At its armature 61 relay 51 short circuits a resistance which is normally in circuit with its lower or polarizing winding so that the relay will now be held in operated position independent of the upper winding as long as the release trunk conductor 40 remains grounded. At armatures 59 and 62 the incoming trunk 55 conductors 38 and 41 are disconnected from

the line relay 53 and retard coil 75, respectively, and are extended instead directly to the trunk conductors 85 and 87 on the outgoing side of the repeater, the bridge across these trunk conductors being opened at the same time. The relays 53 and 54 are now deenergized. In addition to the foregoing relay 51 closes a circuit at its armature 60 which extends from the grounded armature by way of its working contact, armature 57 75 and its resting contact, conductor 39, bank contact 35, wiper 31, armature 18 and its working contact, and the windings of relays 24 and 25 in series to battery. Relay 25 is of relatively low resistance but nevertheless since direct ground has been connected to the conductor 39, both of these relays are energized and a circuit is completed in an obvious manner for the operating magnet of meter M. As stated before, this meter is the one which is associated with substation A on the party line and it is operated when this circuit is closed to register the call. In order to insure that relay 25 will energize slightly ahead of relay 24, and thus guard 80 against any possibility of accidentally operating meter M', relay 24 is provided with a slug of copper on one end of the core and is thus made slightly slow to pull up.

The complete connection having been 85 established the calling and called subscriber may now converse as desired and it will be observed that as soon as the calling line has been extended directly through the repeater D, the transmitter at the calling station will 90 be supplied with talking battery through the windings of the line relay 101 in the connector H, and this relay is now energized over the circuit including the calling line rather than the bridge at the repeater D, as before.

When the conversation is finished both 95 subscribers will hang up their receivers. When the receiver is replaced at substation A, the line and release relays 101 and 102 in the connector H are deenergized and a circuit is completed for the release magnet 110 which operates to restore the connector to 100 normal position in the usual manner. Relay 102 also removes ground from the holding circuit including conductor 92, which has up to this time been effective to maintain the selector switches E and F, and the line switch C, in operated position. When ground is removed from this holding circuit, 105 therefore, the selectors E and F are released and restored to normal, and switching relay 14 in the line switch C is deenergized, thus restoring the line switch C to normal also. The electropolarized relay 51 in the repeater 110 D is also deenergized at this time, and all the apparatus will then be in normal position and ready for use in another connection.

Having explained how the meter M is operated when a call is made from substation A, the process of operating the meter M' 115

- when a call is made from substation A' will now be briefly described. It will be necessary first to call attention to the wiring of the calling devices at the two substations.
- 5 These calling devices are exactly alike but the connections of the shunt springs are slightly different. Considering the calling device S at substation A, the three shunt springs shown are adapted to be closed when 10 the dial is operated and are so connected that whenever the dial is away from its normal position the transmitter and the receiver will be short circuited and the impulse springs will be connected directly 15 across the two sides of the line in series with the primary winding of the induction coil. This is the usual wiring for a calling device of this type, whether it is being used at a party line substation, or not. The calling 20 device at substation A' is connected somewhat differently. The middle shunt spring instead of being connected to the junction of the transmitter and receiver is connected direct to ground, and when the dial is away 25 from its normal position the impulse springs are connected from the negative line conductor 11 to ground. Thus, while the calling device at substation A is adapted to produce 30 interruptions in a circuit including two sides of the line in series, the calling device at substation A' is adapted to produce impulses in a circuit including only one side of the line and ground return.

The operations which take place when the 35 subscriber at substation A' makes a call may now be briefly pointed out. When the receiver is removed the line conductors 11 and 12 are extended by the line switch C into connection with an idle trunk line just 40 the same as in the previous case, and it will be assumed that the trunk line selected is the trunk line which extends through the repeater D to the first selector E. When the line is extended to the repeater D the line relay 53 is energized in series with the retard coil 75, and the two windings of the differential relay 52 as before, and with the same 45 results. The bridge is closed across the trunk line on the outgoing side of the repeater and the selector E is prepared for 50 operation.

The calling subscriber will now operate his calling device in accordance with the first digit in the desired number. When the 55 dial is pulled down the shunt springs are permitted to close and the circuit of the line relay 53 is completed direct to ground at the substation. As a result no current will flow over the lower side of the line, including 60 conductor 12, and the differential relay 52 will be operated by the current flow in its upper winding. Upon energizing, relay 52 closes a circuit for relay 50 at its armature 65, and upon energizing in turn the said relay 50 establishes a locking circuit for itself

at its armature 58. Relay 50 also connects the resistance 77 in series with the conductor 39. When the calling device dial is released it returns to normal and a series of interruptions are produced in the circuit 70 of the line relay 53, which are repeated into the circuit of the line relay of the first selector E and the said selector is operated. During this first series of impulses relays 56 and 55 are energized, as previously explained, the latter relay is locked up, and the differential relay 52 is permanently cut out of the circuit.

The remaining digits in the desired number may now be called and a selector and connector switch, the selector F and connector H for example, are operated to complete the connection to the desired called line, which may be the line of substation A'. When the called subscriber answers, back 80 bridge relay 100 in the connector H is energized and the direction of current flow in the trunk conductors is reversed. Responsive to the current reversal the electropolarized relay 51 in the repeater D is operated 85 and the calling line conductors are connected straight through the repeater. Relay 51 also connects ground to conductor 39 by means of its armature 60, but now since relay 50 has been energized the resistance 77 90 is included in the circuit and the current flow through the relays 24 and 25, although it is sufficient to operate the relay 24, will be insufficient to operate the low resistance and marginally adjusted relay 25. Relay 25, 100 therefore, remains inoperative and a circuit is completed by relay 24 for energizing the operating magnet of meter M', which is thus operated to register the call. The release of the connection takes place when the receiver is hung up at substation A', the same as in the case where the calling subscriber was the subscriber at substation A.

Having described my invention, what I consider to be new and desire to have protected by Letters Patent will be pointed out in the appended claims.

What I claim as my invention is:

1. In an automatic telephone system, a party line, a meter at the exchange for each station on the line, automatic switches at the exchange for use in extending connections, dials at said stations for controlling said switches, and means actuated responsive to the operation of one of said dials to control said switches for determining that the corresponding meter will be operated to register the call.

2. In an automatic telephone system, a party line, a meter at the exchange for each station on the line, automatic switches at the exchange, dials at said stations for controlling said switches, a meter selecting relay, and means responsive to the actuation of a certain of said dials for controlling said

relay to determine which of said meters is to be operated to register the call.

3. In an automatic telephone system, a party line, a meter at the exchange for each station on the line, automatic switches at the exchange for use in extending connections, dials at said stations for controlling said switches, relay mechanism at the exchange for selecting the proper meter for operation when any station makes a call, and means responsive to the actuation of said dial to control one of said automatic switches for controlling said mechanism.

4. In an automatic telephone system, a two party line, a meter at the exchange for each station on the line, automatic switches at the exchange, calling devices at said stations for directly controlling said switches, a differential relay for determining which meter will be operated when either station makes a call, and means for energizing said relay over the calling line responsive to said calling device at the calling station only when the call originates at a particular one of said stations.

5. In a telephone system, a two party line, a meter at the exchange for each station on the line, automatic switches at the exchange, a calling device at one of said stations adapted to selectively control said switches over a circuit including the two sides of the line in series, a calling device at the other station adapted to selectively control said switches over a grounded circuit including only one side of the line, and means at the exchange dependent on which control circuit is used when a call is made for determining which of said meters will be operated.

6. In a telephone system, a two party line, a meter at the exchange for each station on the line, automatic switches at the exchange, a calling device at one of said stations adapted to selectively control said switches over a circuit including the two sides of the line in series, a calling device at the other station adapted to selectively control said switches over a grounded circuit including only one side of the line, and relay mechanism at the exchange controlled in accordance with the control circuit in use when a call is made for determining which of said meters will be operated to register the call.

7. In a telephone system, a party line, a meter at the exchange for each station on the line, automatic switches at the exchange, a calling device at each station generating codes of impulses, a repeater for repeating said impulse codes to said automatic switches to control them, and means in said repeater responsive to circuit conditions in the calling line when any station is making a call for determining which of said meters is to be operated.

8. In a telephone system, a party line, a meter at the exchange for each station on

the line, automatic switches at the exchange, a calling device at each station for generating codes of impulses, a repeater for repeating said impulse codes to said automatic switches to control them, and relay mechanism in said repeater responsive to circuit conditions in the calling line when any station is making a call for determining which of said meters is to be operated.

9. In an automatic telephone system, a party line, a meter at the exchange for each station on the line, automatic switches at the exchange, dials at said stations for controlling said switches, relay mechanism at the exchange for selecting the proper meter for operation when any station makes a call, means for controlling said mechanism responsive to the operation of the dial at one of said calling stations in accordance with the first digit of the called number, and means for operating the selected meter when the called subscriber answers.

10. In a telephone system, a two party line, a meter at the exchange for each station on the line, automatic switches at the exchange, a calling device at one of said stations adapted to selectively control said switches over a circuit including the two sides of the line in series, a calling device at the other station adapted to selectively control said switches over a grounded circuit including only one side of the line, means at the exchange dependent on which control circuit is used when a call is made for determining which of said meters will be operated, and means for operating the selected meter when the called subscriber answers.

11. In a telephone system, a party line, a meter at the exchange for each station on the line, automatic switches at the exchange, a calling device at each station for transmitting impulse codes, repeater for repeating said codes to said automatic switches to control them, means in said repeater responsive to circuit conditions in the calling line when any station is making a call for determining which of said meters is to be operated, and means for operating the selected meter when the called subscriber answers.

12. In a telephone system, a party line, a meter at the exchange for each station on the line, automatic switches at the exchange, a calling device at each station for transmitting impulse codes, repeaters for repeating said codes to said switches to control them, means in said repeater responsive to circuit conditions in the calling line when any station is making a call for determining which of said meters is to be operated, and means for operating the selected meter and for eliminating the repeater from the connection when the meter is operated.

13. In a telephone system, a party line, a

meter at the exchange for each station on the line, automatic switches at the exchange and a repeater for controlling them, a calling device at each station for controlling said repeater, relay mechanism in said repeater responsive to circuit conditions in the calling line when any station is making a call for determining which of said meters is to be operated, said mechanism including a relay in series with the calling line, and means for shunting said relay after the proper meter is selected.

14. In a telephone system, a party line, a meter at the exchange for each station on the line, automatic switches at the exchange and a repeater for controlling them, a calling device at each station for controlling said repeater, means in said repeater responsive to circuit conditions in the calling line when any station is making a call for determining which of said meters is to be operated, means for operating the selected meter when the called subscriber answers, and means for establishing a direct metallic talking circuit through said repeater for conversational purposes.

15. In an automatic telephone system, a party line, a meter at the exchange for each station on the line, automatic switches at the exchange, calling devices at said stations for controlling said switches, a meter selecting relay, and means for operating said relay responsive to the setting of the calling device at a particular one of said stations.

16. In an automatic telephone system, a party line, a meter at the exchange for each station on the line, automatic switches at the exchange, calling devices at said stations for controlling said switches, a meter selecting relay, each of said calling devices having a rotatable dial, and means for operating said relay responsive when the dial at a particular calling device is rotated away from its normal position.

17. In a measured service telephone system, party lines, a plurality of telephone stations assigned to each line, an impulse transmitter at each station, a plurality of meters, each station having one of said meters assigned individually thereto, and means common to said lines and responsive to an actuation of said impulse transmitter for rendering a particular meter operative when the corresponding particular station is used for making a call.

18. In a telephone system, a plurality of party lines having a plurality of substations connected with each line, a register mechanism individual to each of said substations, means common to said lines for selecting one of said mechanisms after the initiation of a call at an associated substation, and means for reversing the current in the calling line to cause the operation of the selected registering mechanism.

19. In a telephone system, a two party line, a meter at the exchange normally connected for registering calls from one of the substations on said line, a second meter for registering calls from the other station, a meter selecting relay for switching the connection from one meter to the other, a ground return circuit closed at one of said stations, after the call is initiated, for controlling said relay, means at the corresponding station for opening the ground circuit during conversation, and means controlled by the response of the called subscriber for operating the connected meter.

20. In a telephone exchange system, a calling telephone line, a plurality of stations thereon, a message register for each station of the line, automatic switching means for extending a connection from the calling line, a circuit for operating the message registers, means common to a plurality of lines for testing the calling line to determine which station of the party line is calling, a switching device individual to the calling line controlled by said testing means for extending said circuit to the message register corresponding to the calling line, and means for closing said message register circuit to actuate said register.

21. In a telephone exchange system, a calling telephone line, a plurality of stations thereon, a message register for each station of the line, automatic switching means for extending a connection from the telephone line, a circuit for operating the message registers, means common to a plurality of lines for testing the calling line to determine which station of the party line is calling, electromagnetic means individual to the calling line controlled by said testing means for extending said circuit to the message register corresponding to the calling line, and means for closing said message register circuit to actuate said register.

22. In a telephone exchange system, a calling line, a plurality of subscribers' substations on said line, a called line, automatic switching mechanism for establishing a connection between said lines, message registers associated with said calling line and individual respectively to said substations, means associated with the several substations for placing discriminatory test conditions on said calling line, means associated with said switching mechanism common to a plurality of lines and responsive to said test conditions, and means individual to said calling line and responsive to said last named means for selecting the message register corresponding to the calling substation.

23. In a telephone exchange system, a calling line, a plurality of subscribers' substations on said line, a called line, automatic switching mechanism for establishing a connection between said lines, message registers

- associated with said calling line and individual respectively to said substations, means associated with the several substations for placing discriminatory test conditions on said calling line, means associated with said switching mechanism common to a plurality of lines and responsive to said test conditions, means individual to the calling line controlled by said second mentioned means for selecting the message register corresponding to the calling substation, and means effective following the successful establishment of the connection for operating the selected register.
24. In a telephone exchange system, a calling line, two subscribers' substations on said line, a called line, automatic switching mechanism for establishing connections between said lines, message registers associated with said calling line and individual respectively to said substations, a switching device individual to the calling line, means at one of said substations for placing a discriminatory ground potential upon one of the conductors of the calling line, means associated with said switching mechanism common to a plurality of lines and responsive to said ground potential for determining the position of said switching device to select the message register corresponding to the calling substation, and means effective upon the successful establishment of the connection for operating the selected register.
25. In a telephone exchange system, a calling line, two subscribers' substations on said line, a called line, automatic switching mechanism for establishing connections between said lines, means at one of said substations for placing a discriminatory ground test potential upon one of the conductors of the calling line, message registers associated with said calling line and individual respectively to said substations, a common operating circuit for said registers, switching means for associating one or the other of said registers with said operating circuit, a relay associated with said switching mechanism common to a plurality of lines and responsive to said test potential for controlling the operation of said switching means to connect the register to the common operating circuit corresponding to the calling station, and means effective upon the successful establishment of the connection for operating the selected register.
26. In a telephone exchange system, a line, a plurality of stations thereon, a cut-off relay, a message register corresponding to each of said stations, a circuit for operating said message registers, and contacts controlled by said cut-off relay for switching any one of said registers to said circuit.

Signed by me at Chicago, Cook County, Illinois, this 25th day of October, 1920.

JOHN WICKS.
